MODULAR STRUCTURAL ELEMENT FOR SWIMMING POOLS

William A. van den Broek, Doylestown, Pa., assignor to
Sylvan Pools, Inc., Doylestown, Pa., a corporation of
Pennsylvania

Filed Oct. 28, 1969, Ser. No. 19,771

Term of patent 14 years

Int. Cl. D25—99

U.S. Cl. D13—1

The sole figure is a perspective view of a modular structural element embodying my invention.

I claim:

The ornamental design for a modular structural element for swimming pools, as shown and described.
